CLAIM

The ornamental design for a base for infant car seat as shown and described.

DESCRIPTION

FIG. 1 is a top, front, left perspective view of a third embodiment of a base for infant car seat in accordance with our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, right, rear perspective view thereof.

The broken lines represent portions of the base for infant car seat in which the design is embodied that form no part of the claimed design.

The dot-dash boundary line in FIGS. 1, 2, 6, 7, and 8 defines the bounds of the claimed design and forms no part thereof.
